US00D881181S

(12) **United States Design Patent** (10) **Patent No.:** **US D881,181 S**
Wright et al. (45) **Date of Patent:** **** Apr. 14, 2020**

(54) **SLEEVE FOR ELECTRONIC DEVICE**

(71) Applicant: **CATALYST LIFESTYLE LIMITED**,
North Point (HK)

(72) Inventors: **Joshua Wright**, Hong Kong (CN);
June Lai, Hong Kong (CN)

(73) Assignee: **Catalyst Lifestyle Limited**, North Point
(HK)

(**) Term: **15 Years**

(21) Appl. No.: **29/672,548**

(22) Filed: **Dec. 6, 2018**

(51) LOC (12) Cl. **14-03**

(52) U.S. Cl.

USPC **D14/250**; D3/218

(58) **Field of Classification Search**

(57) **CLAIM**

The ornamental design for a sleeve for electronic device, as shown and described.

DESCRIPTION

FIG. 1 is a perspective view including a front, top and one side of the sleeve for electronic device;

FIG. 2 is a front elevation view of the sleeve for electronic device of FIG. 1;

FIG. 3 is a rear elevation view of the sleeve for electronic device of FIG. 1;

FIG. 4 is a side elevation view of the sleeve for electronic device of FIG. 1;

FIG. 5 is an opposite side elevation view of the sleeve for electronic device of FIG. 1;

FIG. 6 is a top plan view of the sleeve for electronic device of FIG. 1; and,

FIG. 7 is a bottom plan view of the bottom of the sleeve for electronic device of FIG. 1.

The broken lines depict portions of the sleeve for electronic device that form no part of the claimed design.

1 Claim, 7 Drawing Sheets
